[57] CLAIM

The ornamental design for a combined toy owl and cage charm, substantially as shown and described.

DESCRIPTION

FIG. 1 is a front elevational view of a combined toy owl and cage charm showing my new design;

FIG. 2 is a side elevational view as viewed from the left side in FIG. 1;

FIG. 3 is a side elevational view as viewed from the right in FIG. 1;

FIG. 4 is a rear elevational view thereof;

FIG. 5 is a top plan view thereof;

FIG. 6 is a bottom plan view thereof;

FIG. 7 is a perspective view showing the cage in open condition with the toy owl therein.
